UNITED STATES PATENT OFFICE.

CHARLES G. CONN, OF ELKHART, INDIANA.

KEY-SEAT FOR WIND MUSICAL INSTRUMENTS.

1,223,563.

Specification of Letters Patent.

Patented Apr. 24, 1917.

Application filed June 8, 1915. Serial No. 32,922.

To all whom it may concern:

Be it known that I, CHARLES G. CONN, a citizen of the United States, residing at Elkhart, county of Elkhart, State of Indiana, have invented certain new and useful Improvements in Key-Seats for Wind Musical Instruments, of which the following is a specification.

My invention relates in general to key seats on wind musical instruments, and particularly to the construction of integral key seats on separate pieces of metal. Heretofore key seats which have been provided on the curved metal walls of wind musical instruments, have been produced by forming a separate flange of dimensions appropriate to the key openings to be equipped, and with its inner end shaped to correspond to the curvature of the instrument part and to solder or braze the flange in position. This method as heretofore practised, has long been recognized as unsatisfactory not only from a mechanical stand-point, but principally for musical considerations. The present invention has for its primary object to produce the key seats on a specially constructed metal plate, which plate, after the key seats have been formed, is to be soldered or brazed in position on the tubular wall of the instrument.

A further object of my invention is to provide the plate with suitable means for supporting the key levers, and in this connection a suitable post or bracket may be riveted or otherwise attached to the plate in a position to meet the requirements of supporting the key levers.

As fully explained in the pending application above referred to, it is necessary for musical considerations that there be substantial uniformity in the distribution of the metal forming the flanges of the seats, notwithstanding the fact that the flanges will be higher at some points than at others by reason of projection from a substantially cylindrical surface; for which reason openings are formed, by a suitable punching device, in the plate within the area of the ultimate key openings and these openings are of such shape as to leave between the different points on their perimeter and the perimeter of the circular key openings ultimately to be formed, metal substantially corresponding in dimension to the height of the flanges which such metal is required to form at these points. Suitable dies are then placed

over the metal to be drawn up, with openings corresponding to the external diameter of the flanges to be formed, and a specially formed mandrel is then forced inwardly through the reduced openings to draw the metal into the form of flanges.

The shape of the dies is preferably such that they first act upon the metal corresponding to the deeper portion of the flanges to be formed, and they have circular sections of such diameters as to force the metal out against the surrounding dies when they reach their final positions. After the flanges are thus formed, their edges may be trimmed as by a rotary cutter, or any other suitable means to bring them accurately to the plane in which it is desired to have the key valves seat.

The invention will be more fully understood upon reference to the accompanying drawings, in which—

Figure 1, is a cross section of a wind musical instrument tube showing an embodiment of my present invention.

Fig. 2, is a fragmentary top-plan view of the construction shown in Fig. 1.

Referring to the drawings in detail, 1 represents a metal anchor or base plate which after it has been trimmed to the desired size is subjected to the punching and shaping die.

With a plate thus shaped and having flanges 6, 6^a and 6^b formed on its outer surface, it may be soldered or brazed to the tubular body of the wind musical instrument, with the openings in the respective key seats coaxial with the openings in the body of the instrument. 7 represents a suitable post for supporting the key levers.

While, in its broadest aspect, the present invention consists in forming upon a separate and subsequently attached base-plate, integral key-seats drawn out of the body of the metal, the present invention amounts to something more than the aforesaid. It involves the additional important considerations of insuring substantial hermetic attachment of a key-seat to the body of an instrument by means of an attaching base plate that can be brazed; also such attachment of a plurality of seats all formed on the same base, and therefore greater accuracy in relationship of the seats one to another, and particularly the relationship of a seat offset relative to the medial axial line of the tube to those seats occupying true radial positions

relative to the medial axial line of the tube; and it also provides for conveniently and firmly mounting the key posts without the necessity of perforating the barrel of the instrument.

5 I claim:—

1. In combination with a metallic wind musical instrument tube of substantially cylindrical form, having suitably located key-10 openings in the cylindrical wall; a metal plate conforming to the cylindrical surface of the instrument and intimately united therewith, and having key-openings registering with the key openings of the instrument; said plate having formed thereon, around its said key-openings, integral raised flanges providing key seats.
- 15 2. In combination with a metallic wind

musical instrument tube of substantially cylindrical form, having suitably located key-20 openings in the cylindrical wall: a metal plate conforming to the cylindrical surface of the instrument and intimately united therewith, and having key-openings regis-25 tering with the key openings of the instru-ment; said plate having formed thereon, around its said key-openings, integral raised flanges providing key seats, the bases of said key seats being intimately united through their integral attaching plate to the 30 defining margins of the key-openings in the instrument wall.

The foregoing specification signed at Elkhart, Indiana, this 18th day of May, 1915.

CHARLES G. CONN.
